UNITED STATES PATENT OFFICE.

BERNICE M. BRANSON, OF LINCOLN, NEBRASKA.

DESIGN FOR A BADGE.

No. 39,427.

Specification for Design.

Patented July 21, 1908.

Application filed May 26, 1908. Serial No. 435,182. Term of patent 3½ years.

To all whom it may concern:

Be it known that I, BERNICE M. BRANSON, a citizen of the United States, residing at Lincoln, in the county of Lancaster and State of Nebraska, have invented a new, original, and ornamental Design for Badges, of which the following is a specification, reference being had to the accompanying drawings, forming a part thereof.

The figure is a face view of a badge, showing my new design.

I claim:

The ornamental design for a badge, as shown.

BERNICE M. BRANSON.
